(57) **CLAIM**

The ornamental design for a cyclone dust collector, as shown and described.

DESCRIPTION

FIG. 1 is a right side perspective view of a cyclone dust collector showing my new design.

FIG. 2 is a left side perspective view thereof.

FIG. 3 is a left side view thereof.

FIG. 4 is a right side view thereof.

FIG. 5 is a front view thereof.

FIG. 6 is a rear view thereof.

FIG. 7 is a top view thereof; and,

FIG. 8 is a bottom view thereof.

The details shown in broken lines form no part of the claimed design.
